US00D528210S

(12) **United States Design Patent** (10) Patent No.: **US D528,210 S**
(45) Date of Patent: **** Sep. 12, 2006**

(54) **FASTENING DEVICE FOR DENTAL
PROSTHESES**

(76) Inventor: **Robert Boettcher**,
Ferdinand-LaSalle-Str. 17, Ohrdruf
99885 (DE)

(**) Term: **14 Years**

(21) Appl. No.: **29/221,970**

(22) Filed: **Jan. 24, 2005**

(30) **Foreign Application Priority Data**

Jul. 30, 2004 (DE) 4 04 03 107
Jul. 30, 2004 (DE) 4 04 03 106

(51) **LOC (8) CL** **24-03**

(52) **U.S. CL** **D24/156**

(58) **Field of Classification Search** D24/152,
D24/155-157, 190-192, 199, 180-182, 224;
433/172-174, 193, 102, 3, 50, 53, 114, 141,
433/144; 606/1, 2, 108, 72, 161; 435/141-142

See application file for complete search history.
